UNITED STATES PATENT OFFICE.

ERNEST GORDON BEARD, OF NORTH SYDNEY, NEW SOUTH WALES, AUSTRALIA, AS-
SIGNOR TO UNITED DISTRIBUTORS LIMITED, OF SYDNEY, AUSTRALIA.

AMPLIFYING SYSTEM FOR VACUUM-TUBE CIRCUITS.

Application filed April 22, 1926, Serial No. 103,910, and in Australia November 20, 1924.

This invention relates to improvements in cascade amplification systems for use with radio receiving and transmitting apparatus, wired wireless systems, carrier-wave telegraphy and telephony and the like.

The invention is particularly applicable to radio receiving systems, and it provides a method or system of coupling thermionic amplifying valves in cascade whereby efficient amplification either at radio-frequency or audio-frequency can be obtained over a large band of frequencies. The invention also provides a system of cascade amplification which is suitable for convenient manufacture and can be easily manipulated and controlled even by inexperienced operators.

It is recognized that when thermionic valves are coupled together in cascade for amplification, the most efficient results are obtained when the following four requirements are satisfied:

1. The impedance of the plate circuit of an amplifying valve should equal the internal impedance of the valve.

2. The impedance in the coupling circuit between the plate of one amplifying valve and the grid of the following amplifying valve should be as low as possible.

3. The damping of any valve coupling system due to the plate of the preceding valve should be equalized by the damping of the grid of the following valve.

4. The path from the grid to the plate of a valve should possess infinite impedance, or, alternatively, it should be so balanced by a path for currents or impulses of opposite phase that its effect in no way differs from that of an infinite impedance.

When the fourth requirement is not satisfied the stability of the amplifying system depends on the characteristics of the plate circuit impedance and is effected in the following three ways:

(a) If the plate circuit impedance be inductive, the effective resistance of the grid circuit is lowered and the amplifying system is rendered unstable.

(b) If the plate circuit impedance be capacitive, the resistance of the grid circuit is increased and the amplifying system is rendered stable.

(c) If the plate circuit impedance be resistive only, no effect on the grid circuit

will exist due to the self-capacity of the valve between the grid and the plate. 55

In an endeavor to satisfy the four above set-out requirements, several systems have previously been adopted or proposed, including:

(a) The use of aperiodic transformers. 60

This system, in use, is not very satisfactory and, moreover, it is difficult to operate and control.

(b) The use of tuned transformers.

This system has been successfully used, 65 and it effectively meets the requirements numbered 1 and 2 and to a certain extent the requirement numbered 3, but it has the disadvantage that it can only be used over a very narrow range of frequencies. More 70 satisfactory results are, however, obtainable with this system by using a neutralizing circuit on the "Hazeltine" neutrodyne system, but this addition makes the system very difficult to control. 75

(c) The use of tuned plate circuits.

This system satisfies requirements numbered 1 and 2 but it does not meet the requirements numbered 3 or 4.

(d) The use of resistance capacity couplings between the valves. 80

This system gives good results at low frequency, but at high frequency the results are very unsatisfactory due to the fact that the impedances of the various self-capacities in 85 the plate and grid circuits become considerably less than the impedances of the coupling resistances or chokes.

The present invention relates particularly to improvements in the resistance capacity system of coupling valves for cascade amplification, and its principal object is to remove the limitation above-mentioned, thus enabling efficient amplification results to be obtained at high frequency. 90 95

The invention consists essentially in combining inductances with the self-capacities in the plate and grid circuits of the valves in such a manner as to increase the impedance of the coupling system until it is 100 considerably greater than that of the valve. According to the simplest form of the invention, this is achieved by connecting an inductance (with or without an additional condenser) between the grid and the filament of the following valve. This induct- 105

tance produces in the plate circuit of the valve a resistive impedance which can be made to equal the internal impedance of the valve by adjusting the size of the plate resistance or choke.

Reference is now made to the accompanying drawings, wherein:—

Figure 1 is a diagrammatic view of radio receiving system showing the amplifying valves coupled together in cascade according to one form of the invention.

Figure 2 is a diagrammatic view of the coupling between two valves and wherein a variable coupling condenser is used.

Figure 3 shows a modified form of the invention wherein a condenser is connected across the coupling resistance or choke.

Figure 4 illustrates a form of the invention wherein a resistance or choke is inserted in series with the coupling condenser.

Figure 5 is a view of an alternative form of the invention.

Figure 6 is a diagrammatic view of the coupling between two valves showing one method of balancing-out self capacity between the grid and plate of the following valve.

Figures 7, 8 and 9 are similar views illustrating other methods of balancing-out self capacity between the grid and plate of the following valve.

Referring initially to Figure 1 of these diagrammatic views, 1 indicates the aerial of a radio receiving system, 2 the aerial circuit, 3, 4 and 5 the thermionic valves, 6 the low-tension battery for supplying current to the valve filaments, 7 the filament circuits; 8 the high-tension battery for the valve plates, and 9 the head-phones. The valves are coupled together in cascade by couplings of the resistance capacity type, comprising resistances or chokes 10 and fixed condensers 11.

According to the invention the impedance of each valve coupling is increased by inserting an inductance 12 between the grid and the filament of the following valve. This inductance produces in the plate circuit of the valve a resistive impedance which can be made to equal the internal impedance of the valve, so as to satisfy the requirement No. 1 above, by adjusting the size of the plate resistance or choke 10. If desired, a variable condenser such as 13 may be shunted across each of the inductances 12. The efficiency of the valve coupling system can be improved by satisfying requirement No. 3 above in any one of the following three ways:—

1. By using a variable coupling condenser 14 in lieu of the fixed coupling-condenser 11 and by varying the capacity of this condenser until the required damping condition is obtained—see Figure 2.

2. By connecting a capacity such as the

variable condenser 15, across the coupling resistance or choke 10 and by varying this capacity until the required damping condition is obtained—see Figure 3.

3. By inserting a resistance or choke 16 in series with the coupling capacity 11—see Figure 4. This resistance or choke may have a shunting condenser such as 17.

By any one of the above three methods the damping of the coupling system due to the preceding valve or aerial is equalized by the damping due to the following valve. Furthermore, the impedance of the valve can be equalized by the impedance of the plate circuit, which being either resistive or capacitive will thus give required stability to the circuit.

It is recognized that when cascade coupled valves are naturally regenerative, stability can be efficiently obtained by increasing the current transformation ratio between the valves until the resistance losses are increased to the required degree. Thus, to obtain stability in any of the systems above described, the variable condensers 14 or 15 or the resistance 16 may be so varied as to increase the current transformation ratio between the plate of one valve and the grid of the following valve to increase the power loss as desired.

In an alternative form of the invention illustrated by Figure 5, the requirement No. 3 above is satisfied by connecting a condenser 18 of suitable value across the plate resistance or choke 10 and by inserting a tuning unit 19 in series between the plate and filament of the coupled valves. This tuning unit consists of a variable condenser 20 and an inductance 21, and the grid of the following valve is connected to the high potential end of the said inductance. In this form of the invention the required damping condition is obtained by adjusting the condenser 18 which is connected across the coupling resistance or choke 10. To obtain required stability, the condenser 18 may be varied until the current transformation ratio is of such value that natural regeneration is unable to overcome the resistance losses and still maintain oscillation.

Figure 6 of the drawings illustrates a system wherein any effects due to the self-capacity of the following valve between the grid and the plate are balanced-out whilst still retaining the previously described advantages. In this form of the invention, the plate of a valve is coupled to the grid of the following valve by a blocking condenser 22 in series with an inductance 23 which may be shunted by a capacity 24. The necessary equalization of damping due to the two valves may in this form of the invention be achieved by:—

(a) Connecting a variable condenser 25

between the grid and the filament of the following valve and adjusting this condenser as required—see Figure 6.

(b) Connecting a resistance or choke 26 of suitable value between the grid and the filament of the following valve as is shown in Figure 7, or

(c) Connecting a capacity 27 across the coupling resistance or choke 10 and also by connecting a capacity 28 between the grid and the filament of the following valve, and then adjusting these two capacities as necessary—see Figure 8.

With any of these three systems the effect of the self-capacity between the grid and the plate of the following valve may be balanced-out by introducing extra condensers 29 between the extremities of the inductances 23 and the plate of the following valve, and by adjusting these condensers until the valve plate is at the same high-frequency potential with respect to the extremities of the inductance as is the filament of the valve.

Although the theory under which this circuit operates to produce the neutralization has not been fully established, it is believed that the neutralization effect is probably produced as follows:

The tube 4 (Fig. 7) has parasitic oscillations of much higher frequency than the broadcasting frequency and, if the circuit including the impedance 23 and fixed condenser 24 is in tune with this parasitic frequency it will virtually constitute an infinite impedance. Under these circumstances the circuit at opposite ends of the impedance 23 will be of opposite polarity and consequently the signal fed back from the plate to the grid of tube 4 and through the variable condenser or capacity 29 will reach the end of impedance 23 next the tube 3 in opposite polarity to the signal passing from the plate of tube 4 to the same point. Thus by adjusting the variable condenser 29 the two signals of opposite polarity may be made of equal strength at this point and will neutralize.

In another form of the invention illustrated by Figure 9 of the drawings, the balancing effect previously described is obtained by using an inductance 30, in the plate circuit of each valve and by inserting another inductance 31, suitably proportional to the inductance 30, in the grid circuit of the following valve. The plate of each valve is then coupled to the grid of the following

valve by means of a condenser 32 of suitable size, and balancing condensers 33 and 34 are connected across the extremities of said coupling condenser 32. This system is much simpler to control than the well-known neutrodyne system wherein the grid is balanced in relation to the plate. In lieu of the balancing condensers 33 and 34, inductances of suitable value may be employed if so desired.

The valve coupling systems herein described may be readily applied to coupling an aerial to the grid of the first valve of a wireless receiver in order to equalize the radiation damping of the aerial with the damping due to the first valve of the receiver. This may be accomplished by connecting the aerial 1 to the grid of the first valve by means of an inductance 35 and a capacity 36 in parallel—see Figure 8. A condenser 37 is connected between the grid and the filament of the valve, and balancing condensers 38 and 39 are connected from the plate of the valve to the extremities of the inductance 35. In this form of coupling the filament is earthed and the damping due to the grid of the valve is varied as required by adjusting the condenser 37.

When using any of the coupling systems or methods embodied in the invention, the selectivity of the couplings may be increased to any desired degree by so adjusting the circuits that the damping due to the preceding valve or aerial is reduced below that requisite for maximum efficiency.

To simplify the control and the operation of wireless receivers using the improved couplings, the inter-valve coupling capacities may be first switched into use when the additional circuits embodied in the invention are successively brought into use in any sequence.

What I do claim is:—

In an amplifying system for vacuum tube circuits, a plurality of vacuum tube amplifiers arranged in cascade, a circuit connection between the plate of one tube and the grid of the following tube, a capacity in said connection, an inductance in said circuit in series with said capacity, a capacity in shunt with the inductance, and balancing capacities connected between the extremities of said inductance and the plate of the following tube.

In testimony whereof I affix my signature.

ERNEST GORDON BEARD.
